Primary Examiner — Cynthia Ramirez(74) *Attorney, Agent, or Firm* — Potter Anderson Corroon LLP; Rakesh H. Mehta, Esq.(57) **CLAIM**

The ornamental design for a tube fitment for use with a valve fitment for dispensing fluids, as shown and described.

DESCRIPTION

FIG. 1 illustrates a perspective view of the tube fitment showing our new design;

FIG. 2 illustrates a view of the tube fitment from the front thereof;

FIG. 3 illustrates a view of the tube fitment from the left side thereof;

FIG. 4 illustrates a view of the tube fitment from the back thereof;

FIG. 5 illustrates a right side view of the tube fitment thereof;

FIG. 6 illustrates a top view of the tube fitment thereof;

FIG. 7 illustrates a bottom view of the tube fitment thereof; and,

FIG. 8 illustrates a perspective view of the tube fitment in the back view thereof.
